(57) **CLAIM**

The ornamental design for a TNT cup, substantially as shown and described.

DESCRIPTION

FIG. 1 is a front perspective view of a TNT cup, showing my new design;

FIG. 2 is a front view thereof;

FIG. 3 is a rear view thereof;

FIG. 4 is a first side view thereof;

FIG. 5 is a second side view thereof;

FIG. 6 is a top plan view thereof; and,

FIG. 7 is a bottom plan view thereof.

The broken lines in the drawing depict environmental subject matter only and form no part of the claimed design.
